(57) **CLAIM**

The ornamental design for a gazebo, as shown and described.

DESCRIPTION

FIG. 1 is an isometric view of the gazebo of the instant invention, said gazebo having three sides of identical design and one open side;

FIG. 2 is a side view of the gazebo, said side view typical of three sides;

FIG. 3 is an external corner view of the gazebo; and,

FIG. 4 is a top view of the gazebo.
